UNITED STATES PATENT OFFICE.

ALFRED SWENSEN, OF CICERO, ILLINOIS, ASSIGNOR TO THE CABLE COMPANY, OF CHICAGO, ILLINOIS, A CORPORATION OF ILLINOIS.

AIR-PUMP.

1,336,396.

Specification of Letters Patent.

Patented Apr. 6, 1920.

Application filed April 21, 1916. Serial No. 92,604.

To all whom it may concern:

Be it known that I, ALFRED SWENSEN, a citizen of the United States, residing at Cicero, in the county of Cook and State of Illinois, have invented new and useful Improvements in Air-Pumps, of which the following is a full, clear, concise, and exact description, reference being had to the accompanying drawing, forming a part of this specification.

My invention relates to air-pumps.

One of the objects of my invention is to provide an improved air-pump, which will be simple and compact in construction and quiet and efficient in operation.

Further objects will appear from the detailed description to follow, taken in connection with the appended claims.

In the drawings, in which one embodiment 20 of my invention is shown;

Figure 1 is a front elevation of my improved air-pump;

Fig. 2 is a horizontal section, substantially on the line 2—2 of Fig. 1;

Fig. 3 is a vertical section of the pump, substantially on the line 3—3 of Fig. 2;

Fig. 4 is a detailed sectional view, substantially on the line 4—4 of Fig. 3, showing one of the inlets to the pump;

Fig. 5 is a view of the fixed leaf-member of one of the bellows of the pump, showing the inlet-valve; and

Fig. 6 is an elevation of one of the bellows of the pump as viewed from the left in Fig. 1.

Referring now to the drawings in detail, the air-pump shown comprises a quadrangular suction or wind chest 10 in the form of a box open at opposite ends, to the sides of which are secured four suction bellows, or exhausters, 11, and driving mechanism 12 for operating these exhausters 11 to withdraw the air from the wind-chest 10. The wind-chest 10 comprises four similar, substantially rectangular, trough-like wall-members 13, which are recessed or grooved at 14 to form communicating passages or channels, which passages or channels are covered by the bellows 11 to form the chamber of the wind-chest.

The wall-members 13 are recessed at their ends to receive the supporting bars 15, with which the bellows 11 form an air-tight joint.

The bellows 11 are similar in construction and the description of one will suffice for all.

Each comprises a fixed leaf-member, or board, 16, suitably secured to the adjacent wall-member 13 to form an air-tight joint therewith, and a movable leaf-member 17, connected to the leaf-member 16 by means of a flexible fabric 18. The fixed leaf-member 16 has a series of inlet-ports 19, through which the air flows from the wind-chest to the interior of the bellows. A flap check-valve 20 prevents air from flowing out of the bellows 11 through the ports 19 as the bellows is collapsed. The movable leaf-member 17 is provided with a series of ports 21, through which the air from the bellows escapes as the bellows is collapsed. A flap check-valve 22 prevents air from entering the bellows 11 through the ports 21 as the bellows expands.

The driving mechanism 12 comprises a belt-drive-wheel 23; a crank-shaft 24, to which the drive wheel 23 is secured, having crank-arms 24^a and a crank-pin 24^b; four driving yokes 25, one for each of the bellows 11; and four bearing-blocks 26 of any suitable material, as bronze, one for each of the yokes 25. Each of these bearing-blocks 26 is provided with approximately a half-bearing 26^a, for engagement with the crank-pin 24^b, and is secured to its yoke 25 in any suitable manner, as by a screw 27. These bearing-blocks 26 are connected together in pairs by means of flexible straps 28 of suitable material, such as leather, secured to the bearing-blocks 26 by means of screws 29, each bearing-block 26 being connected to a bearing block directly opposite. These flexible straps prevent disengagement of the bearing-blocks 26 from the crank-pin, and also act as washers to prevent end-knocking. By arranging the bearing-blocks in pairs, compactness is secured, as the crank-pin can be made shorter than if they were not paired.

In order to relieve the straps 28 of the strain due to the resistance of the bellows to collapsing, the movable leaf-members 17 of the bellows are connected together in pairs by means of U-shaped members 29^a, pivotally connected with the leaf-members by means of screws 29^b. Because of their U-shape, these members 29^a form spring-contracting members for holding the half-bearings 26^a in engagement with the crank-pin 24^b. Each driving yoke 25 is connected with its respective bellows by means of a cross-bar 30, which lies in a recess 31 in the mov-

able leaf-member of the bellows and which is held in place in this recess by means of metal bearing-plates or strips 32, secured to the leaf-member in any suitable manner, as by screws 33. The crank-shaft 24 is mounted in suitable bearings 34, secured to supporting-strips or plates 35 on opposite sides of the wind-chest. Spacing-blocks 36 may be placed between the sides of the wind-chest 10 and the supporting-strips 35 to properly position the latter. To prevent endwise movement of the shaft 24, a collar 37 may be secured to the shaft by means of a set-screw 38. A ball-bearing collar 39 is positioned 15 upon the shaft between the hub of the wheel 23 and the nearby supporting-strip 35. A bent wire spring 40, pivoted at 41 to the supporting-strip 35, bears on this collar 39 to prevent the shaft 24 from knocking in its bearing 34. The hooked end 42 of this spring engages beneath a stud, or button, 43, to hold the spring firmly against the collar 39.

Air enters the wind-chest 10 through two inlet-conduits. One of these conduits comprises the tubing 44, a curved nipple 45 over which the tubing 44 fits, a sleeve 45^a in which the curved nipple 45 fits, a tubular lining 46 over which the sleeve 45^a fits, and a hollow block 47 in which the lining 46 fits. The tubular lining 46, the hollow block 47, and the fixed leaf-member 16 of the bellows are provided with registering openings 49, 50, and 51, respectively, affording communication between the interior of the wind-chest and the tubular lining 46. The other conduit comprises the tubing 52, which fits over the nipple 53, which fits into the block 54, which block is provided with a passage 55 affording communication between the interior of the wind-chest and the nipple 53. The check-valves 20 and 22 are substantially the same, and the description of one will suffice for both. Each comprises 40 a sheet 56, of leather or other suitable flexible material; a cross-bar 57, secured to one end of the sheet 56 (the other end of the sheet 56 being secured to the leaf-member of the bellows in any suitable manner); a wire spring 59, the bent end 60 of which engages the cross-bar 57 to tend to hold the flexible sheet 56 taut; and the wire spring 61, having one end secured to the leaf-member of the bellows, and the other end engaging the 55 flexible sheet 56 for closing the valve.

In pumps of the bellows type, as now constructed, the inlet and outlet check-valves being controlled simply by the existing pressures, the outlet-valve opens simultaneously 60 with the closing of the inlet-valve, and this renders the operation noisy. To prevent this simultaneous operation of the inlet and outlet check-valves, an abutment 62 is provided for engaging the outlet check-valve 65 just before the bellows reaches the limit of

its expanding movement. This abutment may take the form of a flexible metal strip, having a bent-over end 63 located in position to engage the outlet flap check-valve, as shown in Figs. 1 and 6. The end 63 engages the check-valve and holds it closed until the corresponding inlet check-valve has been seated, so that the two valves are not operated simultaneously. This abutment also prevents any sudden popping 70 open of the outlet check-valve, as the valve can start to open only as fast as the movement of the movable leaf-member of the bellows away from the end 63 will permit. Also, the fact that this outlet-valve is closed 75 until some time after the inlet-valve is seated 80 will tend to deaden the noise due to the seating of the inlet-valve.

Any suitable lubrication device, such as a grease-cup 64 and tube 64^a, may be provided for lubricating the crank-shaft 24. For securing the pump to a support, a plurality of L-shaped clips 65 may be secured to the wind-chest 10. These clips are formed with key-shaped slots 66 for co-operation with headed supporting-devices, such as screws. These screws are located on the support in position to enter the enlarged part of the key-shaped slots, after which the pump is slipped down to cause 90 the shanks of the screws to enter the narrower part of the key-shaped slot. In this position, the heads of the screws will prevent the clips from becoming disengaged from the screws. After the clips have been 95 slipped over the screws, the latter may be tightened up, to hold the pump securely in position.

The operation of the pump is as follows: The belt-drive-wheel 23 is driven by power 105 from any suitable source, causing the crank-shaft 24 to rotate to reciprocate the driving yokes 25 to cause the bellows 11 to be alternately expanded and collapsed. As each bellows expands, a partial vacuum is created therein, and air flows in through the tubing 44 and 52 to the wind-chest 10, through the inlet-ports 19, past the inlet-valve 20, to the interior of the bellows. As each bellows collapses, the pressure in the 110 bellows rises above that in the wind-chest, causing the inlet-valve 20 to seat and prevent the escape of air from the bellows into the wind-chest. The outlet check-valve 22 then moves away from the abutment 62, and 115 the air within the bellows is forced out through the ports 21 and past the valve 22.

By means of the yoke connection between the bellows and the crank-shaft, the driving force is transmitted equally to opposite sides 125 of the movable leaf-members of the pump-bellows.

It will be seen that a pump of this construction, with the polygonal wind-chest, the bellows mounted on the outer sides of the 130

chest, and the crank-shaft extending within the chest permits the largest possible capacity of pump-bellows in a given space, and makes an extremely compact construction.

5 In musical instruments of the class with which these pumps are used, space and compactness are important, since the dimensions of the instrument case may not be increased, 10 in any direction, and the pump must be fitted into the case along with a considerable amount of other mechanism. It is also important that the pump-bellows have a comparatively large area in order that the

15 capacity of the pump may be sufficient when the bellows are driven at a comparatively slow speed, this slow speed being highly desirable in order to prolong the life and efficiency of the pump and to insure proper lubrication. These two desirable features (comparatively large area of pump-bellows and compactness) are obtained by arranging the pump-bellows on the outside of the wind-chest.

20 25 In a construction in which the bellows are arranged inside the wind-chest, the bellows must be circumscribed by the inside dimensions of the wind-chest. Furthermore, any one of the pump-bellows may not extend 30 from corner to corner inside such a wind-chest but must terminate enough short of one corner to permit the bellows of another side to occupy, and operate in, that corner, or, in other words, clearance must be provided 35 between the free end of the movable leaf-member of one bellows and the pivoted end of the movable leaf-member of an adjacent bellows. Furthermore, the completed 40 pump construction would involve adding the thickness of the polygonal wind-chest all around this arrangement of pump-bellows.

Having thus described my invention what I claim as new and desire to secure by Letters Patent is:—

45 1. An air-pump comprising a rotatable crank-shaft, a wind-chest extending around the crank portion of said shaft, a plurality of exhausters supported on the outside of said wind-chest and in communication there- 50 with, and driving connections between each exhauster and the crank-shaft comprising a yoke embracing the wind-chest for transmitting force from the crank-shaft to the exhauster.

55 2. An air-pump comprising a rotatable shaft, a polygonal wind-chest extending around said shaft, a plurality of bellows one secured to each side of the wind-chest, and driving connections between said shaft and 60 bellows, each side of said wind-chest comprising a member having a groove, the grooves of adjacent sides being in communication with each other, said bellows each having a fixed leaf-member covering one of 65 said grooves and said bellows having ports

therein affording communication between said grooves and said bellows.

3. An air-pump comprising a bellows having a movable leaf-member and inlet and outlet ports, a check-valve movable with 70 said leaf-member for preventing air from entering said bellows through said outlet-port, an abutment located in position to close said check-valve as the bellows expands, and a second check-valve for preventing air from escaping from said bellows through 75 said inlet-port.

4. An air-pump comprising a bellows having a movable leaf-member and inlet and outlet ports, a check-valve movable with 80 said leaf-member for preventing air from entering said bellows through said outlet-port, a yielding abutment located in position to hold said check-valve closed for a time as the bellows starts to collapse, and a 85 second check-valve for preventing air from escaping from said bellows through said inlet-port.

5. An air-pump comprising a bellows having a movable leaf-member and inlet and 90 outlet ports, a check-valve movable with said leaf-member for preventing air from entering said bellows through said outlet-port, a yielding abutment located in position to hold said check-valve closed for a 95 time as the bellows starts to collapse, and a second check-valve for preventing air from escaping from said bellows through said inlet-port, said yielding abutment being positioned to engage the check-valve before the 100 bellows is fully expanded.

6. An air-pump comprising a polygonal wind-chest, a rotatable shaft centrally located with respect to said wind-chest, a plurality of bellows, one secured to each side 105 of the wind-chest on the outside thereof, a plurality of air-pressure-operated check-valves, one for each bellows, for controlling the communication between said wind-chest and said bellows, respectively, and driving 110 connections between said shaft and bellows.

7. An air-pump comprising a rotatable crank-shaft having a crank-pin, a pair of bellows mounted on opposite sides of said shaft, each bellows having a leaf-member 115 movable toward and from said shaft, driving connections between said shaft and said movable leaf-members, each driving connection comprising a sectional bearing engaging the crank-pin, said sectional bearings 120 being located substantially opposite each other, and means connecting the movable leaf-members for holding the sectional bearings in engagement with the crank-pin.

8. Two opposed pumpers; a revoluble 125 shaft having a crank therewith and between the said two pumpers; pitmen from said crank to each said pumper; and a connecting member between the said two pumpers, the ends of said connecting member at- 130

tached to both said pumbers; the positions of said ends being on a line extended through said shaft, the intermediate part of said connecting member offset to one side 5 of the said shaft.

9. An air-pump comprising a polygonal wind-chest and a plurality of bellows-members, one for each side of said wind-chest; said wind-chest comprising a plurality of 10 substantially flat rectangular chambered members united end to end to form a box-like structure open at opposite sides, said rectangular members each being provided with an open channel, said channels being 15 in communication with each other, and a plurality of substantially flat cover-members for covering said channels, respectively.

10. An air-pump comprising a polygonal wind-chest, a plurality of bellows-members, 20 one for each side of said wind-chest, and a plurality of cover-members, one for each side of said wind-chest; said wind-chest comprising a plurality of substantially flat rectangular members united end to end to 25 form a box-like structure open at opposite sides, said rectangular members being provided with outwardly-open channels, said channels being in communication with each other, each of said cover-members comprising 30 a substantially flat member secured on the outside of said wind-chest over one of said channels.

11. An air-pump comprising a polygonal wind-chest and a plurality of bellows-members, one for each side of said wind-chest; said wind-chest comprising a plurality of 35 substantially flat rectangular members arranged end to end to form a box-like structure open at opposite sides, each of said rectangular members being provided with an open channel and each channel being covered by a bellows-member.

12. An air-pump comprising a rotatable crank-shaft, a wind-chest comprising two 40 chambers located on opposite sides of said 45 crank-shaft, two exhausters, and driving

connections between the crank-shaft and each of said exhausters; each of said chambers lying between said crank-shaft and one of said exhausters, and each chamber being 50 in communication with one of said exhausters.

13. An air-pump comprising a rotatable crank-shaft, a wind-chest comprising a plurality of chambers located around said 55 crank-shaft, a plurality of exhausters, and driving connections between said crank-shaft and each of said exhausters; each of said chambers being located between said crank-shaft and one of said exhausters, and 60 each chamber being in communication with one of said exhausters.

14. An air-pump comprising a rotatable crank-shaft having a crank-pin, a pair of bellows mounted on opposite sides of said 65 shaft, each bellows having a leaf-member movable toward and from said shaft, driving connections between the crank-pin and movable leaf-members respectively, each driving connection comprising a sectional 70 bearing engaging the crank-pin, the sectional bearings being located substantially opposite each other, and spring means for holding the sectional bearings in engagement with the crank-pin.

15. An air-pump comprising a rotatable crank-shaft having a crank-pin, a pair of bellows mounted on opposite sides of said 75 shaft, each bellows having a leaf-member movable toward and from said shaft, driving connections between the crank-pin and said movable leaf-members respectively, each driving connection comprising a sectional bearing engaging the crank-pin, the sectional bearings being located substantially 80 opposite each other, and spring means connecting the movable leaf-members for holding the sectional bearings in engagement with the crank-pin.

In witness whereof I have hereunto sub- 90 scribed my name.

ALFRED SWENSEN.

It is hereby certified that in Letters Patent No. 1,336,396, granted April 6, 1920, upon the application of Alfred Swensen, of Cicero, Illinois, for an improvement in "Air-Pumps," errors appear in the printed specification requiring correction as follows: Page 1, line 105, after the word "spring" strike out the hyphen; same page, lines 105-106, between the words "contracting" and "members" insert a hyphen; page 3, line 2, after the word "chest" insert a comma; same page, line 9, after the word "increased" strike out the comma and insert the word *materially*; and that the said Letters Patent should be read with these corrections therein that the same may conform to the record of the case in the Patent Office.

Signed and sealed this 22d day of June, A. D., 1920.

[SEAL.]

M. H. COULSTON,
Acting Commissioner of Patents.
